13 Claims. (Cl. 179—100.4)

1

This invention relates to improved transducers, such as microphones or phonograph pick-ups, for converting mechanical movements into electrical signals. More particularly it relates to a novel kind of transducer which includes a gas discharge valve arranged therein to afford great power sensitivity and a very low output impedance.

Substantially all of the transducers of the prior art, including those of the vacuum tube types, have been incapable of delivering (or controlling) more than extremely small amounts of power. Because of this most sound transmitting and sound reproducing systems have included audio amplifiers between their transducers and reproducers. The presence of amplifiers in these systems has made them more costly and has been largely to blame for what may be called poor overall conversion efficiencies. The latter fact is due to a multiplication of the individual losses entailed in the numerous energy conversions required in the amplifiers, such as in the conversion of heater current into thermionic emission; in the conversion of A. C. line power into suitable direct potentials for amplifier tube anodes; and in the conversion of the high impedance of the output tube(s) of the amplifier to a suitable value for matching that of the reproducer. An example of an undesirable result of poor "overall conversion efficiency" is that the life of batteries employed in portable phonographs is much less than what it might be ideally.

It is an object of the present invention to devise improved transducers capable of controlling the delivery of such large amounts of power to utilization devices, such as transducers, that the need for amplifiers as in the prior art is very much reduced or eliminated.

It is a further object of the present invention to devise improved transducers capable of controlling the delivery of large amounts of power directly to a low impedance load, such as a reproducer, without the need of an impedance transformer.

In general, these objects have been attained by devising a transducer, which controls the current in a utilization circuit by the use of a novel type of gas tube valve. The internal impedance of this valve has an extremely low average value which is variable over a usefully large range in response to microscopic mechanical movements such as those imparted to a phonograph stylus. As a result the transducer is able directly to modulate the flow of electrical energy through a closed load circuit between a low-voltage external source, such as a battery consisting of one or a

few 1½ volt dry cells, and a low impedance reproducer. The low impedance of the gas tube valve results from the fact that the load current which it controls passes from its cathode to its anode 5 not as an electron discharge across an insulating open space but as a conduction current through a dense plasma. Valving action is effected by a control electrode which varies the over-all series resistance offered by the plasma to this conduction current in such a way that the electrode does not lose control when the tube is ionized. In this way this gas tube can modulate the load current as a substantially linear function of an externally applied control, i.e. it can operate in 15 a manner corresponding to a class A hard tube amplifier rather than as a dual stability on-off gas tube switch.

In the drawing:

Figure 1 represents a longitudinal sectional view of one phonograph pick-up embodiment of the present invention. The section is taken along the line 1—1 of Figure 2 and in a plane which is vertical when the pickup is in its operating position (resting on a horizontal flat phonograph record);

Figure 2 represents another longitudinal sectional view of the embodiment of Figure 1, this section is taken along the line 2—2 of Figure 1 and in a plane perpendicular to that of the section of Figure 1;

Figure 3 represents a view of a longitudinal section of a modification of the embodiment of Figures 1 and 2 taken in the same manner as the section of Figure 2;

Figure 4 represents a view of a longitudinal section of another modification of the embodiment of Figures 1 and 2, this section also being taken in the same manner as that of Figure 2;

Figure 5 represents a view of a longitudinal section of another embodiment of the present invention, the section being taken along the line 5—5 of Figure 6 in the same manner as that of Figure 2;

Figure 6 represents a view of a longitudinal section of the embodiment of Figure 5 taken along the line 6—6 of Figure 5 in the same manner as the section of Figure 1;

Figure 7 represents two conditions of the ion sheath which surrounds the grid wires of the embodiment shown in Figures 5 and 6 during operation thereof for two different spacings of these wires with respect to the adjacent anode;

Figure 8 represents a sectional view of another embodiment of the present invention. The section is taken along the line 8—8 of Figure 9 in a

plane which is vertical when the pick-up is in its operating position (resting on a horizontal flat record) and is transverse to the long axis of a pick-up arm in which the pick-up is carried;

Figure 9 represents another sectional view of the embodiment of Figure 8. This section is taken along the line 9-9 of Figure 8 in a plane at right angles to that of the section of Figure 8;

Figure 10 is a schematic circuit diagram of a sound reproducing system using the pick-up device shown in Figures 1 and 2 or the device shown in Figure 4;

Figure 11 is a schematic circuit diagram of a sound reproducing system using the pick-up device of Figure 3;

Figure 12 is a schematic circuit diagram of a sound reproducing system using the pick-up device shown in Figures 5 and 6; and

Figure 13 is a schematic circuit diagram of a sound reproducing system using the pick-up device shown in Figures 8 and 9.

The pick-up 10 shown in Figures 1 and 2 comprises a gas-tight envelope 11 of substantially rectangular shape. Most of the envelope 11 is made of rather thick glass and is quite rigid. However, its bottom 12 comprises a flexible, disc-shaped portion (disc 13) consisting of a circular, relatively thin metal diaphragm formed with a number of concentric corrugations and having its entire periphery fused to the edges of an opening in the glass part of the bottom.

A rigid stylus 14 is carried in, and extends and is sealed through, the center of the disc 13. In this arrangement, and due to the flexibility of the disc, transverse vibrations imparted to the needle point 14a on the external end of the stylus 14 are imparted (with a reversal of direction) to its internal end. In other words the center (f) of the disc acts as a fulcrum for the stylus at a point intermediate its external and internal ends.

There are two internal load current paths through pickup 10. Each of the paths extends between a main cathode 15 and a respective one of pair of anodes 16, 17. A device for controlling the current between the cathode 15 and the anodes 16, 17 is herein designated "control grid" 18, this name being used because of its function rather than because of its structural appearance. The grid 18 includes a slot 19 which is partially blocked to provide two mutually exclusive paths for electron current from the cathode 15 to the respective anodes 16, 17. One of these paths extends through each of two long narrow openings 22 which are formed along the edges of the slot 19 by blocking the center of the slot with a grid-shutter 20. The long axis of the shutter 20 coincides with an upward extension of the axis of the stylus 14 on the internal end of which it is mounted. In the rest position of the stylus the long axis of the shutter also coincides with the long axis of the slot 19. In this arrangement a transverse vibration of the stylus will move the shutter 20 within the slot 19 so as to increase one of the openings 22 and at the same time decrease the other. It will be apparent to those skilled in the art that this type of arrangement is appropriate for utilization of this pick-up in a push-pull load circuit. As appears most clearly in Figure 2 the stationary portion of the grid 18 comprises a central partition 21 which shields each of the anodes 16, 17 from the other. In addition it serves to prevent electron current which passes through a given opening 22 toward

one of the anodes 16 or 17 from being collected on the other anode.

In the operation of this device both the stationary part of the grid 18 and its movable shutter 20 may be at the same potential. Because of this these parts may be electrically interconnected as shown at 26. The stationary portion of the grid 18 is supported on one of the end walls of envelope 11 by a rod 23. Rod 23 is shown to extend through this wall to the outside of the envelope to provide a terminal pin for connection to an external circuit element.

In the operation of pick-up 10 the electron current between the cathode 15 and either of the anodes 16, 17 is through an extremely low impedance ionized gas plasma. In the novel gas valve employed herein, this plasma is established within the tube by ionizing its gaseous filling G by the action of an independent or auxiliary electron current flow. The auxiliary current flow is readily distinguishable from the load current flow through the tube. The following are two points of distinction: the auxiliary flow includes as one component a "space discharge" electron current (as distinguished from "conduction" electron current) in which electrons attain sufficient velocities to ionize the gaseous filling, G, of the tube; and (2) the overall path of this space charge is different from that of the load current, e.g., it starts at an emissive electron source other than that at which the load current path starts this is the case herein where the two paths start at different cathodes, or it terminates at a collector other than the anode for the load current path, or it both starts and terminates at different electrodes than the internal load current path.

An auxiliary cathode 24 is mounted within the envelope 11 on the far side of the main cathode 15 from the group of elements including the anodes 16, 17 and grid 18. It is surrounded by a cylindrical shield 25 having a narrow slot 27 on its side toward the main cathode 15. The shield causes the ion-producing electron discharge to be formed as a directed stream having a narrow cross section, i. e., a "constriction," in the region just beyond the point where the electrons emerge from the slot 27. With this type of construction a plasma of very high density, and therefore of very high conductivity, can be provided by an auxiliary electron discharge of surprisingly low current, i. e., it can be economically provided.

The shield 25 is supported on a rod 28 which in the example herein is fused through an end of envelope 11 to serve as a terminal pin. This construction makes it possible to use a circuit in which one can control the bias between the auxiliary cathode 24 and the shield 25. This can be useful as a way of electrically varying the amount of constriction produced by the shield 25 without physically changing the width of its slot 27. However, it is entirely feasible to operate the auxiliary cathode and the shield at the same potential. Therefore, for some embodiments the shield 25 may simply be mounted by one or more rods which are secured to the interior of the envelope at suitable presses without necessarily extending any of the rods through to the outside of the envelope. In such an arrangement an internal inter-connection may be used for causing the shield and the auxiliary cathode to have the same potential. Moreover, as indicated by extensive experimentation, it is also feasible simply to allow this shield to "float."

In order not to include unnecessary detail in the drawing, and because the cathodes which appear in the various figures may be of any of a number of suitable types known in the art, none of these cathodes is shown in section. In general, indirectly heated types of cathodes (particularly for main cathodes) are to be preferred for a number of reasons, e. g., their greater rigidity (than filamentary cathodes) and the resultant freedom from microphonics; the reduced likelihood of hum when A.-C. heater current is used; and the more copious emission of electrons.

Each of the pick-up devices shown herein may be processed in any of a number of ways well known in the art to provide a gaseous filling within its envelope prior to sealing off. Any suitable gas or mixture of gases may be utilized. The gas pressure for a particular pick-up will be in accordance with its specific electrode geometry and spacings and must be such as to favor the formation of a self-sustaining ionizing discharge. A number of gas tubes of the kinds employed in the present pick-ups have been found to operate satisfactorily with a filling of helium at a pressure of approximately 750 microns. However, as is well known other gases and other pressures may be used, e. g., gas pressures which lie within the range between approximately 100 microns and several millimeters of mercury.

The embodiment shown in Figure 4 is a modification of that shown in Figures 1 and 2. For this reason, these embodiments include a number of elements which are substantially identical. Where like elements appear in a number of the figures herein they bear the same reference characters. The modification (of the transducer of Figure 4 over that of Figures 1, 2) is in the structure of its control grid 18a. The stationary portion of grid 18a comprises a plurality of slots 19a rather than a single one like the single slot 19 of grid 18. Accordingly the movable portion is a grid shutter 20a consisting of a plate which has the same number of similarly spaced slots and which overlays the slotted front of the stationary portion of the grid 18a, rather than a narrow strip (like 20) which is inserted between the edges of a single slot (like 19). In the rest position of the stylus 14, i. e., when there is no force acting to deflect it transversely, each slot in plate 20a will be aligned with one-half of the open area of a respective one of the slots 19a. As a result if the tube is built symmetrically and if the emission from the cathode 15 is substantially uniform all around its periphery, substantially equal currents will be received on the two anodes 16, 17. This is desirable in circuits such as that shown in Figure 10, in which the attainment of equal and opposite direct current components in the push-pull load circuit currents will obviate any necessity of mechanically or otherwise biasing the voice coil 31. It also tends to cancel certain noise-components such as any 60 cycle hum which may arise from the use of A.-C. heater current. The groups of slots located on opposite sides of the center axis of plate 20a uncover halves of respective slots 19a which are oppositely positioned with respect to the center lines of those slots, i. e., which are positioned to the right and left thereof. As a result, a transverse displacement of the plate 20a will increase all openings providing current paths to one of the anodes and simultaneously decrease all of those providing current paths to the other.

Figure 10 is a circuit diagram of a sound reproducing system employing either a pick-up device of the kind shown in Figures 1 and 2 or the modification thereof shown in Figure 4. The utilization device in this system is a transducer 30 having a center-tapped voice coil 31. Each of the anodes 16, 17 is connected to a different end of the voice coil 31. The primary source of electrical energy for driving the voice coil 31 is a low voltage battery 33. This battery may consist of a few large-size, series-connected one and one-half volt dry cells (as few as one or as many as 6 or 7) and it should be capable of delivering an average output of the order of at least $\frac{1}{2}$ ampere. The main cathode 15 is connected to the negative side of the battery 33, this connection being made, as shown herein, over a path through ground. In the operation of this device large currents of the order of one or more amperes may circulate through the load circuit even though the potential drop between either of the anodes 16 or 17 and the cathode 15 is no greater than one or two volts. With a hard tube that is not hundreds of times larger than this pick-up, this would not be at all possible. One reason for this is that the emission from the cathode of a hard tube is space-charge-limited when its control grid is biased for class A operation. Moreover, such currents would not even be possible in a gas tube (despite its freedom from space-charge-limited cathode emission) if it be of the prior art type in which the ionizing electron current moves between the same electrodes as the load current. This is due to the fact that the current must not exceed the value at which the IR drop in the external circuit will cause the applied voltage to be reduced below the value needed for sustaining ionization. Gas tubes in which the ionizing current moves between the same electrodes as the load current have the additional shortcoming that a grid through which those currents pass to reach an anode invariably loses control once the tube is ionized. The reasons for this have been understood for some time: the negatively biased grid gathers about itself a "sheath" of positive ions which determines the effective average or quiescent size of the grid openings; an instantaneous signal voltage superimposed on the bias varies this average size so that one might expect it to exert a valving effect on the current; however, an effect of this is that the constriction of the stream of ionizing current, which exists wherever it passes through a grid opening, also varies and this produces a variation in the plasma density which so opposes the change in the effective resistance of the grid that a substantially constant current continues to flow regardless of the signal voltage variations. In other words, as a change in the cross sectional area of the plasma in the plane of the grid varies its resistance in a region near to the grid, a change occurs in its density which oppositely varies its resistance. Instead in a gas tube which operates on the principle of the device shown herein the plasma is produced by an auxiliary source so that its density is not so influenced by variations in the thickness of an ion sheath around a grid for controlling load current. Therefore, an effective variation in the size of a control grid opening will actually cause a change in the load current. It will do so since there will be nothing to simultaneously influence the plasma density so as to produce an equal and opposite change in its overall conductivity.

in the load current path. In view of the foregoing it is obvious that mechanical variations in the grid openings of the devices of Figures 1 and 2 and 4, though they may have some action akin to constricting the load current where it passes through the grid openings, will not have any general effect upon the plasma density which will offset the valving action of the grid. Any electron discharge which accompanies the electron conduction in the load current flow will be at too low a velocity to contribute to the production of plasma and therefore its variations will not affect the plasma density. The grids 18 or 18a shown herein are effective control devices because mechanical variations in the size of their load-current carrying openings vary the useful cross section of the conductive plasma in the plane of those openings, i. e., vary the cross sections of the corridors of plasma which extend through them.

A further disclosure of principles governing the operation of a gas tube of this type is to be found in a co-pending application of E. O. Johnson, Serial No. 185,745, filed September 20, 1950. From the foregoing, it is apparent that the control grid should be biased at a somewhat negative direct potential if it is to be responsive to an externally applied signal voltage. This is because the effectiveness of the signal depends on the existence of an ion sheath which it can control to vary the effective size of the grid openings. Since the plasma extends through the openings its conductivity in the region of the grid will therefore be controllable by variations in the potential thereof. In the devices shown in Figures 1, 2 and 4 herein substantially the same thing is accomplished by simply mechanically altering the actual physical size of the grid openings through which the plasma extends to the anodes. In other words a grid of the kind shown herein is able to control the load current without dependence on the formation of a sheath, and therefore does not need to be negatively biased. Accordingly, it may be operated at any of a variety of positive potentials at none of which it will be surrounded by a positive ion sheath. On the other hand, a variable negative bias may be applied to the grid, as shown at 40 in Figure 10, as a way of providing a control parameter. Since the existence of this bias will cause a sheath to form and its magnitude will determine the thickness. Therefore, this arrangement provides a way of adjusting the size of the load-current-carrying openings through the grid when the stylus is at rest and may be used as a gain control. The auxiliary electron current in either the Figs. 1, 2 pick-up or in that of Figure 4 flows from the auxiliary cathode 24 to the entire group of the elements constituting its load current carrying-and-valving portion. Accordingly, a circuit employing the pick-up should include a source of direct potential 34 by which the auxiliary cathode is polarized far enough below the potential of at least one of these elements to sustain an ionizing electron discharge between the auxiliary cathode and that element. As previously mentioned the constriction of the ionizing current caused by the use of the slotted shield 25 makes it possible to maintain a relatively large potential drop across the auxiliary discharge. Because of this the electrons will attain ionizing velocities when they have traversed only a relatively small portion of their paths of travel. Since they will continue to produce ions as they move over the rest of their

paths a relatively very dense plasma will be produced for a given magnitude of ionizing current. This plasma will bathe the main cathode 15 and extend through the grid openings to the anodes 16, 17 thereby neutralizing the electron space charge of the main cathode and providing a highly conductive medium in the load current path of the tube. It is advantageous to use grid openings which are large enough so that some electrons of the ionizing discharge current will be projected through them to produce plasma directly in the space between the grid and each anode and/or so that plasma may freely diffuse thereinto from the space around the main cathode. In fact, for best operation of any of these pick-ups, the plasma should extend continuously from the main cathode(s) to the main anode(s).

It will be apparent, from the fact that variations of conductivity are effected by varying the cross sectional area of the plasma rather than by varying its density, that the frequency response of this pick-up does not have an upper limit which is a function of deionization time. Actual tests indicate that this type of device has a frequency response which far exceeds the limits required for high fidelity audio reproduction.

The embodiment of Figure 3 is intended for simple class A operation, for example, in a circuit like that of Figure 4, rather than for push-pull operation. To this end it is a modification of the Figure 4 embodiment in that only a single anode 29 is used and the structure of its grid 18b is simplified accordingly.

The embodiment shown in Figures 5 and 6 differs from all of the others thus far described in that a different type of grid control is employed. The control grid 35 for this embodiment does not consist of two portions, one stationary and one movable. Instead the entire grid is a unitary structure and movable as such. This structure comprises a base plate 36 of an approximately triangular shape which is carried on the top end of the stylus 14 as it appears in Figure 6. A row of grid wires 37 extends upward from the top surface of the plate 36 along each of two of its sides. Each row of wires is parallel and closely adjacent to one of the anodes 16a and 17a.

This embodiment normally requires that the grid be negatively biased so that a sheath of ions surrounds each of the grid wires. This is best understood with reference to Figure 7. Figure 7 shows how the conductive corridor (of plasma) 38 which extends to an anode (17a) between the sheaths 39 around two adjacent grid wires varies in length as the grid wires are moved with respect to the adjacent anode. Though the plasma is a highly conductive medium, it does have a finite resistance and the value of that resistance for each corridor 38 is directly proportional to its length. Therefore, the resistance of the plasma to a given anode will increase as the grid is moved away from it.

A circuit which is suitable for the Figures 5 and 6 embodiment is shown in Figure 12. The operation of this circuit will be readily understood in view of the foregoing explanation of the circuit shown in Fig. 1.

The Figs. 8, 9 embodiment includes a gas valve which operates in a somewhat different way to control electron conduction through the load current path of the pick-up. In this embodiment the means for modulating the over-all conductivity of the plasma operates by varying its density over most or all of the load current path

rather than by varying its useful cross-sectional area in a small region of said path near the plane of a control grid. While this necessarily means that the frequency response of this pick-up will be limited at its upper end by de-ionization time, nevertheless, the useful frequency range will be more than adequate to cover the entire audio frequency range. A further disclosure of principles governing the operation of a gas tube of this type is to be found in a co-pending application of William M. Webster, Jr. Serial No. 197,014, filed November 22, 1950. As will be best understood with reference to Figure 9, certain elements of this embodiment which are related to the function of producing the ionizing electron discharge include what are essentially the cathode, control grid, and anode of what may be called an auxiliary triode. More specifically these elements are: the auxiliary cathode 24; a movable control grid 41; and a slotted anode 42. In the operation of the tube, the potential of the slotted anode 42 is positive with respect to the auxiliary cathode 24 but its magnitude is less than that required to produce ionization.

Some of the electrons which are attracted from the auxiliary cathode 24 toward the slotted anode 42 will be projected through its slot 43 and upon emerging from its will move toward a group of electrodes including those which carry the useful load currents within the pick-up. Since the "auxiliary triode" is operated with such a low anode potential, it will behave like a vacuum tube rather than a gas tube, i. e., its grid can be used to effect plate current variations in a substantially linear fashion over a usefully large range. It can be made to do this either by keeping the mu constant and changing the grid voltage or by doing the converse. As is well known the mu of a triode can be varied by changing the spacing between its cathode and control grid. This principle underlies the arrangement used herein. In this pick-up the stylus 14 is connected to the underside of a base plate 44 of the control grid 41 in such a manner that a transverse movement thereof will tilt the base plate and will thereby alter the grid-cathode spacing between a U-shaped row of grid wires 45 (which extend upward from the base plate) and one side of the auxiliary cathode. Thus, with an appropriate value of grid bias between the grid and this cathode, the current of the electron discharge in this triode section can be modulated by mechanical movements of the stylus. As a result the magnitude of the current of the portion of this discharge which escapes through the slot in the anode will likewise vary and this, in turn, will directly control the production of plasma in the right hand portion of the tube.

In the arrangement shown herein, it is desirable to prevent or inhibit any tendency of positive ions to drift from the right hand region of the tube back through the slot 43 into the interelectrode spaces of the auxiliary triode where their presence would tend to impair its proper operation. Accordingly, means are provided herein for trapping positive ions in two low potential troughs from which it will be difficult for them to escape so as to be free to move toward the triode section. A first low potential trough may be established just beyond the slotted anode 42 by properly polarizing a first screen grid 46 which extends across the path of the electrons which emerge therefrom. In the operation of this device, this screen is maintained at a potential above that of the auxiliary cathode but below

that of the slotted anode. As a result of the electrons which, as explained above, will emerge from the slot at velocities too low to produce ionization, will be retarded (but not stopped) so as to emerge from the right hand side of the screen at even lower velocities. The next element in the path of these electrons is an accelerating screen 47. In the normal operation of the pick-up, this screen is maintained at a potential somewhat above the ionizing potential of its gaseous filling G. In this arrangement it is to be expected that at least some of the electrons approaching the accelerating screen 47 will have ionizing collisions slightly before they reach it and that for this reason positive ions will be present to the left of this screen (as it appears in the drawing). However, any leftward movement of these ions will be limited as most of them will be attracted into and trapped within the low potential trough of the first screen grid 46. Of course, the inertia of some of these ions will be sufficient so as to tend to carry them all the way up the left slope of the potential trough. However, most of these will lose much of their inertia in collision with slow ions. Moreover, most of those which do get up the left slope will collide with solid portions of the slotted anode 42 so that only a few will pass through its slot 43. The slower ions will oscillate leftward and rightward through the first screen grid 46 thereby remaining trapped in the trough which it establishes and eventually they will be collected and neutralized on the first screen grid 46. Most of the ionizing collisions will occur in a second low potential trough to the right of the accelerating screen 47 in which, therefore, a dense plasma will be established. It is in this region that the main source of thermally emitted electrons is located. This source in the present example is a pair of indirectly heated cathodes 48. The main anode 49 is mounted to the right of these cathodes. It may be polarized at the same potential as the accelerating screen 47 while the two cathodes 48 are polarized at a potential a few volts below it, i. e., below the common potential for these two elements. In this way, a low potential trough will be established between the accelerating screen 47 and the main anode 49 in which trough positive ions will tend to be trapped. This is the load current carrying portion of the pick-up. The load circuit battery 33, which is used for maintaining the small potential difference between the main source of electrons (the pair of cathodes 48), and the accelerating screen 47 and the main anode 49, respectively, should be a high current source, such as a number of series-parallel-connected 1½ volt dry cells, a storage battery, or the like, since it must serve not merely for establishing a bias but also for delivering to the utilization device a signal-bearing current having an average value of the order of one to several amperes. In this embodiment the plasma not only has the impedance-lowering effects described above, including, of course, that of neutralizing the electron space charge of the main cathodes. In addition it is variable, under control of the auxiliary triode to have an impedance-modulating effect on which the valving action of the pick-up depends. During operation of the pick-up the electron discharge current which issues from the slot 43 is modulated in accordance with the mechanical movements of the stylus 14. This will modulate the density of the plasma trapped in the right hand portion of the tube and thereby will modulate the large currents which pass through it.

11

If desired, the control grid 41 may be eliminated from the "auxiliary triode" by using an arrangement in which movements of the stylus 14 are caused to vary the spacing between the auxiliary cathode 24 and the slotted anode 42, e. g., by moving either one of these elements while the other is held stationary.

The Figs. 8, 9 pick-up may be modified to produce an embodiment which is suitable for push-pull operation by providing on the left hand side of the auxiliary cathode 24 a duplicate set of the electrodes which are shown on its right in the drawing. As a result the pick-up would comprise two auxiliary triodes each having its own slotted anode but both having the same cathode and control grid. In such an embodiment, a portion of the control grid would lie to the left of the auxiliary cathode 24 just as a portion of the grid 41 lies to its right as shown in Figs. 8 and 9 as a result each transverse movement of the grid would increase the current passed by one of the auxiliary triodes and at the same time decrease that passed by the other.

Figure 13 shows a circuit which is suitable for using the Figs. 8, 9 pick-up device as explained above.

I claim:

1. A transducer comprising: a sealed envelope containing a gaseous filling; within the envelope a group of load circuit electrodes including at least a main cathode and a main anode having, respectively, electron-emitting and electron-receiving surfaces which define the opposite ends of a predetermined load current path; means for producing an ionizing discharge of electrons along a different path within said envelope to provide a conductive plasma which is continuous from one end to the other of said load current path; a flexible portion for said envelope; and means responsive to mechanical forces exerted externally of said envelope and communicated to its interior over said flexible portion for varying the over-all conduction provided in the load current path by said plasma.

2. A transducer as in claim 1 in which said last mentioned means comprises a means responsive to said forces to vary the over-all density of said plasma to vary said conduction provided by it.

3. A transducer as in claim 1 in which said last mentioned means comprises a means responsive to said forces to vary in a predetermined region along said load current path the cross-sectional area of the plasma usefully available for conduction of load currents to thereby vary the over-all conduction provided in the load current path by the plasma.

4. A transducer comprising: a sealed envelope containing a gaseous filling; within the envelope a group of load circuit electrodes including at least a main cathode and a main anode having, respectively, electron-emitting and electron-receiving surfaces which define the opposite ends of a predetermined load current path; means for producing an ionizing discharge of electrons along a different path within said envelope to provide a conductive plasma which is continuous from one end to the other of said load current path; a flexible portion for said envelope; said group of load circuit electrodes also including a movable element comprising a control grid having openings which are in alignment with the load current path and are large with respect to the mean free path of a positive ion, said grid being in close spaced relationship to the main

12

anode; and means linking said movable element to the inside of said flexible portion for varying the closeness of said spaced relationship in response to mechanical forces exerted externally of said envelope, whereby said forces will be effective to vary the lengths of plasma corridors extending through the grid openings to the main anode.

5. A transducer comprising: a sealed envelope containing a gaseous filling; within the envelope a group of load circuit electrodes including at least a main cathode and a main anode having, respectively, electron-emitting and electron-receiving surfaces which define the opposite ends 10 of a predetermined load current path; means for producing an ionizing discharge of electrons along a different path within said envelope to provide a conductive plasma which is continuous 15 from one end to the other of said load current path; a flexible portion for said envelope; said group of load circuit electrodes also including a control grid having at least one slot aligned with the load current path of said main anode, said grid including a movable element positioned 20 effectively to define a perimeter of the slot, and said movable element being linked to the interior 25 of said flexible portion of the envelope to act as a shutter for varying the cross-sectional area of the plasma where it extends through the slot 30 in response to mechanical forces exerted externally of said envelope and communicated to its interior from said flexible portion.

35 6. A transducer as in claim 5 in which said control grid surrounds said main anode and except where it is slotted constitutes a continuous shield between it and other electrodes of said transducer.

transducer.

7. A transducer comprising: a sealed envelope containing a gaseous filling; within the envelope a group of load circuit electrodes including at least a main cathode and a main anode having, respectively, electron-emitting and electron-receiving surfaces which define the opposite ends of a predetermined load current path; means for producing an ionizing discharge of electrons along a different path within said envelope to provide a conductive plasma which is continuous from one end to the other of said load current path, said means including as two of its elements an emissive source of ionizing electrons and a collector thereof, at most only one of two said elements being included in said group of load circuit electrodes; a flexible portion for said envelope; a lever sealed through said flexible portion to extend from the interior of said envelope to its exterior whereby a movement imparted to the external portion of the lever will be reproduced at its internal portion; and means within the envelope including a movable element which is mechanically linked to the internal portion of said lever for responding to movements thereof to vary the overall conduction provided in the load current path by the plasma.

8. A transducer as in claim 7 in which said emissive source of ionizing electrons is an auxiliary cathode and said collector comprises one of said group of electrodes such as said main cathode.

9. A transducer comprising: a sealed envelope containing a gaseous filling; within the envelope a group of load circuit electrodes including at least a main cathode and a main anode having, respectively, electron-emitting and electron-receiving surfaces which define the opposite ends of a predetermined load current path; means

for producing an ionizing discharge of electrons along a different path within said envelope to provide a conductive plasma which is continuous from one end to the other of said load current path; a flexible portion for said envelope; and means responsive to mechanical forces exerted externally of said envelope and communicated to its interior over said flexible portion for modulating the ionizing discharge to correspondingly modulate the density of said plasma.

10. A transducer as in claim 9 in which said means for producing an ionizing discharge includes an auxiliary cathode as a source of ionizing electrons and at least one of said group of load circuit electrodes as a collector thereof; and said last mentioned means comprises a control grid movably supported in close and variable space relationship to the auxiliary cathode on its side toward said group of electrodes and linked to said flexible portion for control of said relationship in accordance with said mechanical forces.

11. A transducer as in claim 10 in which said main anode is on one side of said main cathode and said auxiliary cathode and said control grid are on the other and which further comprises means, including at least one electron permeable screen positioned athwart the path of the ionizing discharge between the auxiliary cathode and the control grid, for establishing a low potential ion-trapping trough in a region near said main cathode whereby the concentration thereof will be much greater in said load current path than in the region between said auxiliary cathode and said control grid.

12. A transducer comprising: a sealed envelope containing a gaseous filling; within the envelope a main cathode and a main anode having surfaces defining the opposite ends of a predetermined load current path; means for producing an ionizing discharge of electrons along a different path within said envelope to provide a continuous plasma over all of said load current path; a control grid for blocking the movement of electrons over some of the lines of travel, between the main cathode and the main

anode, over which such travel would otherwise be possible, but having at least one opening so that it does not block their movement over others of said lines of travel; a flexible portion for said envelope; said control grid comprising a movable shutter-portion, linked to the interior of said flexible portion of the envelope and positioned to define a perimeter of said opening, for responding to externally exerted mechanical forces imparted to it over said flexible portion to vary in the cross-sectional area of said plasma where it extends through the opening.

15. A sound reproducing system comprising: a transducer including a sealed envelope containing a gaseous filling, within the envelope a main anode and a main cathode having surfaces defining the ends of a predetermined load current path, and means including as two of its elements an emissive source of ionizing electrons and a collector thereof for producing an ionizing discharge of electrons along a different path within said envelope to provide a conductive plasma which is continuous from end to end of said load current path, and means responsive to mechanical forces exerted externally of said envelope for varying the over-all conduction provided in the load current path by the plasma; a low impedance reproducer; a load circuit including in series said reproducer and a high current source of electrical energy, for applying between the main anode and main cathode a potential of insufficient magnitude to ionize said gaseous filling; and an ionizing circuit for applying between said two elements a potential of sufficient magnitude to ionize said gaseous filling.
